UNITED STATES PATENT OFFICE.

JACOB S. HASKELL, OF SALEM, MASSACHUSETTS.

WRITING-TABLE.

Specification of Letters Patent No. 21,832, dated October 19, 1858.

To all whom it may concern:

Be it known that I, JACOB S. HASKELL, of Salem, county of Essex, and State of Massachusetts, have invented a new and useful Improvement in the Construction of 5 Writing-Tables, called the "Revolving Writing-Table," of which the following is a full and exact description.

Drawing Number 1 represents a side elevation; Number 2 a plan with the cover removed; Number 3 a plan with the cover and small drawers removed, and the large drawer A, pushed in to the position for fastening the small drawers, showing the 15 circular fastening rods Y and Z. Numbers 4 and 5 show a plan and side of the fastening rods.

The same letters refer to like parts in all the drawings.

20 The support of the table may be of any suitable form or design, to which the body of the table is fastened by a circular bolt upon which it may freely turn. The body of the table may contain horizontal drawers 25 of such number, size, and arrangement as convenience, fancy, or taste may suggest. In this table I have one large drawer and ten smaller ones, all moving in the lines of the respective radii which pass through their 30 centers.

The advantage of having books and papers lying on various parts of a large table, or in some of the numerous drawers, easily moved within the reach of a person 35 sitting at the table, would be in a degree lost by the necessary expense of locks, at the outset, and the trouble of taking up the key, unlocking and locking each drawer and replacing the key each time one or more of 40 them is used. This difficulty is obviated by having some one of the drawers, as A, provided with suitable slides so that it may be pushed a few inches into the vacant space

in the center X, and removing a portion of the adjacent pieces which form the partitions, M and O, as shown at m' and o' . 45 These spaces (m' and o') contain knobs upon the ends of the curved rods X and Y, and by which the said rods may be operated. These rods are let into the lower board of 50 the body of the table, so that the upper surfaces of both are flush, and passing under the portion blocks M, N, W, V, and U, and O, P, Q, R, and S, respectively. Upon the upper surface of these rods, at distances 55 from the knobs corresponding with the distances of the nearest side of the smaller drawers from the said knobs, there are projections m , n , w , v , and n and o , p , q , r , and s , respectively, which enter correspond- 60 ing indentations in the drawers B, C, L, K, and I, and D, E, F, G, and H respectively, when the said rods are moved (by means of the knobs m' and o') in a direction from the drawer A, making a full and complete 65 fastening, and rendering all locks unnecessary. When the rods are moved in a direction toward the drawer A, the smaller drawers are unfastened so that the fastening and unfastening of all the drawers is 70 effected by the sliding of the rods Y and Z, and the locking and unlocking of the drawer A in the usual manner.

What I claim and wish to secure by Letters Patent is— 75

The arrangement of the circular bolt with and for fastening of the several drawers substantially as and for the purpose specified.

In witness whereof, I have hereunto subscribed my name the sixth day of September eighteen hundred fifty eight. 80

JACOB S. HASKELL.

In presence of—

JOSEPH L. LONGEE,
CHAS. W. FELT.
